(57) **CLAIM**

The ornamental design for an L-shaped scarf, as shown and described.

DESCRIPTION

FIG. 1 is a perspective view of the L-shaped scarf.

FIG. 2 is a top plan view of the invention.

FIG. 3 is a right side view of the invention, the left side view being a mirror image.

FIG. 4 is a bottom plan view of the invention.

FIG. 5 is a front elevation view of the invention.

FIG. 6 is a rear elevation view of the invention; and,

FIG. 7 is a perspective view of the invention in use on a wearer of the L-shaped scarf.

The broken lines in FIG. 7 are for purposes of illustration only and form no part of the claimed design.
